LUGGAGE LOCK OR SIMILAR ARTICLE

David Levine, New York, N. Y., assignor to Crest Lock

Company, Inc., New York, N. Y.

Application January 12, 1952, Serial No. 18,025

Term of patent 14 years

(Cl. D50—7)

Fig. 1.

Fig. 2.

Fig. 1 is a perspective view of a luggage lock or similar article showing my new design; and

Fig. 2 is a side view of said lock.

The dominant features of my design are shown in full lines. The rear of the lock is conventional.

I claim:

The ornamental design for a luggage lock or similar article, substantially as shown and described.
